UNITED STATES PATENT OFFICE.

WILLIAM H. CALNAN, OF CLINTON, IOWA.

PORTABLE DISTRIBUTING-MACHINE.

1,139,844.

Specification of Letters Patent. Patented May 18, 1915.

Application filed August 30, 1913. Serial No. 787,484.

To all whom it may concern:

Be it known that I, WILLIAM H. CALNAN, a citizen of the United States, residing at Clinton, in the county of Clinton and State of Iowa, have invented certain new and useful Improvements in Portable Distributing-Machines; and I do hereby declare the following to be a full, clear, and exact description of the invention, such as will enable others skilled in the art to which it appertains to make and use the same.

This invention is a device to be used in the construction of pavements for pouring and distributing melted pitch, tar, cement or other binding and filling material into the crevices or joints between rows of paving blocks and the like.

The objects of the invention are, first, to produce a light, cheap, practical portable machine which can distribute or pour the binding or filling material into the crevices or on the surface of pavements, and which can be rapidly operated to direct the binding material into crevices or over surfaces; second, to so construct the machine that the parts, which are liable to become coated or caked with the material through use, may be instantly cleaned; third, to allow for an interchange of parts to adapt the device for varying widths of paving blocks and the like; fourth, to permit the ready removal of parts which become obstructed or clogged through caking of the material from the reservoir without a change in the fluid control mechanism; fifth, to control the flow of the filling material through the discharge spouts.

The machine or device comprises a suitable reservoir, of the portable type, to hold the filling or binding material, said reservoir being provided with one or more discharge spouts having suitable valve means for controlling the flow of the material from the reservoir as required, the valves acting simultaneously with all the spouts, or independently as may be required. The spouts are provided also with a suitable reaming or cleaning means to prevent choking of the fluid passages.

In the accompanying drawings, Figure 1 is a side elevation, partly in section, of a multiple spout pouring machine embodying the invention. Fig. 2 is a front elevation of a multiple spout pouring machine. Fig. 3 is a fragmentary view of removable spout plates. Fig. 4 is a transverse section of an

individual discharge spout and valve member showing the cleaning device, and Fig. 5 is a vertical sectional view of another embodiment of the invention disclosing separate valve operating devices.

Like reference characters refer to like parts in the several figures.

In the preferred embodiment of the invention as shown in the accompanying drawings, A represents a reservoir of any suitable construction which is supported by a truck or carriage having wheels, B, whereby the machine or device can be transported over the surface to be treated. In the construction shown, the reservoir A, preferably having an open upper end, is provided at opposite sides with stud axles or trunnions, b, on which the wheels B, are journaled. For the proper transportation of the machine, handles C, are used which are secured to, and project rearwardly from suitable supporting means, such as brackets c, to which the axles are secured.

For the purpose of allowing an interchange of spouts for filling crevices between paving blocks of different widths, there is provided a removable plate D, which is secured to lower end of reservoir A by suitable bolts d, which pass through holes in said plate D, and through a flange a, on reservoir A. The spout plate D contains one or more fluid directing elements or spouts, E, suitably spaced for the purpose of distributing the material over desired surfaces.

In order to control the flow of the filling or binding material from the reservoir A, through the spouts E, manually controlled valves F, are used. The valve F is shown in Fig. 4 as connected to the lower end of a rod f, which rod is pivoted at its upper end to bell-crank lever f¹, mounted on a transverse shaft G, which is connected by an arm of lever f¹ to a valve operating rod 100 f², extending to a handle f³.

In order to separately control the flow of the filling or binding material from the reservoir A, through the individual spouts E, manually controlled valves F are shown in Fig. 5. Each valve F, is therein shown connected to the lower end of a rod f which is pivoted at its upper end to bell-crank lever f¹ mounted on a standard G¹. In this embodiment, the standard G¹ is secured to the top edge of reservoir A, and is connected through an arm of lever f¹ to the valve

operating lever or handle f^2 . A rod H may be employed whereby an operator may control the action of each individual valve or open and close all valves simultaneously. 5 A pointed plunger I is provided to afford means of readily cleaning the opening through the spouts E and to prevent obstructions or choking by particles of the filling material. This plunger I is a continuation of the valve rod f , and the pointed end thereof is adapted to pass through the spout E when the valve F is closed or seated, and to be freed from said spout E when the valve F is opened to permit the flow 10 through the spout.

To allow for the ready removal of spout points which may become worn through constant friction with the paving blocks over which they are drawn, removable spout 20 points may be provided which are attached by suitable screw means to the spouts E .

It will be understood that the construction and arrangement of parts may be varied to suit the different conditions of use, and that 25 the invention is not restricted to the precise construction shown and described.

Having thus described my invention, what I claim as new is:

1. In a machine of the character described, 30 a substantially rectangular reservoir, one end of which is contracted to form an elongated discharge mouth, a flange pro-

truding from the wall of the reservoir at the discharge mouth, a single discharge spout plate adapted to be removably secured to 35 said flange to close said mouth, a plurality of nozzles carried by the spout plate, a valve for each nozzle, separate actuating devices for each of said valves to operate the valves independently, a pivot rod common to all of 40 said actuating devices, and means whereby all of said valve actuating devices may be operated simultaneously.

2. In a machine of the character described, 45 a reservoir, the base of which is out of parallel alinement with top thereof, said base and front wall being projected forwardly and converging toward an elongated mouth, a spout plate adapted to be secured to said mouth, a plurality of nozzles carried by the spout plate, a valve for each nozzle, separate actuating devices for each of 50 said valves to operate the valves independently, a pivot rod common to all of said actuating devices, and means whereby all of 55 said valve actuating devices may be operated simultaneously.

In testimony whereof, I affix my signature, in presence of two witnesses.

WILLIAM H. CALNAN.
